(57) **CLAIM**

The ornamental design for a femoral prosthesis insertion tool, as shown and described.

DESCRIPTION

FIG. 1 is a perspective view of a femoral prosthesis insertion tool illustrating my new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a rear end elevation view thereof; and,

FIG. 7 is a front end elevation view thereof.

Broken lines appearing in the several views form no part of the claimed design. Unclaimed subject matter is shown in broken lines for the purpose of illustrating the environment in which the article embodying the design is used.
